UNITED STATES PATENT OFFICE.

JOSEPH BIJUR, OF NEW YORK, N. Y., ASSIGNOR, BY MESNE ASSIGNMENTS, TO BIJUR MOTOR APPLIANCE COMPANY, A CORPORATION OF DELAWARE.

GEARING.

1,279,501

Specification of Letters Patent. Patented Sept. 24, 1918.

Application filed April 7, 1911. Serial No. 619,489.

To all whom it may concern:

Be it known that I, JOSEPH BIJUR, a citizen of the United States, residing at New York, in the county of New York and State of New York, have invented certain new and useful Improvements in Gearing, of which the following is a full, clear, and exact description, such as will enable others skilled in the art to which it appertains to make and use the same.

This invention relates to electrical generating apparatus for automobiles and with regard to the more specific features thereof, to the driving mechanism and associated parts of such apparatus. One of the objects thereof is to provide efficient and practical means for mounting and driving an electric generator for automobiles and the like which shall be economical in consumption of space and readily adaptable to meet various conditions. Another object is to provide apparatus of the above nature of simple and cheap construction and which is not susceptible to dirt or dust or liable to injury. Other objects will be in part obvious and in part pointed out hereinafter.

The invention accordingly consists in the features of construction, combinations of elements and arrangements of parts which will be exemplified in the construction hereinafter set forth, and the scope of the application of which will be indicated in the following claims.

In the accompanying drawings, wherein are shown one or more various possible embodiments of the several features of this invention,

Fig. 1 is a diagrammatic elevation showing the same mounted in position;

Fig. 2 is a sectional elevation taken substantially through the center of the same;

Fig. 3 is an end view of the part shown in Fig. 2;

Fig. 4 is a detail elevation of a swinging casing member or support;

Fig. 5 is a similar view of a casing taken from the opposite side;

Fig. 6 is an end view indicating a method of assembling the parts;

Fig. 7 is a sectional elevation of the entire embodiment of certain features of the invention; and

Fig. 8 is an end view thereof.

Similar reference characters refer to simi-

lar parts throughout the several views of the drawings.

Referring now to Fig. 1 of the drawings in detail, there is shown at 1 an internal combustion engine of the automobile type provided with a crank shaft 2, from which is driven, by the gears 3, a shaft 4 having thereon the pump 5 and magneto 6, respectively communicating with the jacket water system 7 and ignition system 8. By reason of the disposition of the above and other apparatus, as the stern post diagrammatically indicated at 9, there remains adjacent shaft 4 a cramped space only, in which is positioned an electrical generating device 10.

As best shown in Fig. 2, the generator 10 is provided with an armature shaft 11 having bearings 12 and 13 and having fixed thereon a pinion 14. Bearing 13 is incased within an annular shoulder 15 and journaled upon the outer side of this shoulder is a swinging support or casing member 16. This member, the shape of which is best indicated in Fig. 4 of the drawings, has mounted therein a pin 17 upon which is loosely journaled a power-transmitting gear 18 of greater diameter than the pinion 14 and formed constantly to mesh therewith as the member 16 is swung about the collar 15.

Mounted upon shaft 4 is a driving gear 19 adapted to mesh with the gear 18, and by reason of the multiplication of speed from the latter to the pinion 14, this gear need not be of large diameter. Moreover, as gear 18 is constantly in proper relation to the pinion, it is necessary merely that it be swung into mesh with the gear 19 in order to complete an efficient drive, and, hence, the armature shaft need not be positioned at any predetermined distance from shaft 4. Thus, by my invention, I avoid the practice of designing a special dynamo drive for every design of engine, having due regard in every case for the choice of a convenient location for the dynamo not already occupied by another accessory or accessories of the engine. I achieve this result by providing a drive which may be standard for any power reduction and which is inherently adapted to make a power connection with the dynamo regardless where, within limits, the assembler may be compelled to locate said dynamo with respect to the engine. By reason of this feature a large de-

gree of freedom in the mounting of the generator is attained and it may readily be efficiently positioned and driven even though the available space is cramped. Obviously the drive would be complete and efficient even though the gear 18 is not disposed directly between gear 19 and pinion 14. There are provided in the member 16 set-screws 20 whereby the parts may be locked in proper position and this part has formed therein screw-holes 21 in the flange 22, by which it supports a casing 23, best shown in Fig. 5 of the drawings.

Casing 23 is longitudinally split, as at 15 24, and is provided with coacting pairs of ears 25 to secure its halves in assembled position. It is supported upon the casing member 16 not only by the screws in the holes 21 but by screws 26 as shown in Fig. 3. 20 In the use of the above described embodiment, the generator is mounted in any convenient position, which may be offset from the shaft 4 either vertically or horizontally, or both. The gear 18 is then swung into 25 proper mesh with gear 19 and locked in position by the set-screws 20. The casing 23, the parts of which are separated, is then fitted about the shaft 4 and assembled by means of the ears 25 and secured in position 30 upon the swinging casing member 16. The drive is then complete from shaft 4 to the armature with the desired multiplication of speed and without the necessity for using large gears or carefully mounting the generator in a predetermined position. It is to be understood that if it is desired to mount the generator with the gear 18 offset from the plane of shafts 11 and 4, there will be used a casing 23 of such form as to permit 35 this arrangement of the parts. This casing not only protects all the gearing from the effect of dirt and dust, but guards the teeth of the vulnerable portions from the injury due to the use of hammers, wrenches or other tools upon the engine or its accessories.

In Figs. 7 and 8, there is shown a slightly different embodiment of this invention, in which the pin 27 is somewhat longer than 50 the corresponding pin 17 of the first described construction and has mounted thereon a pinion 28 fixed to the gear 18 of a materially smaller size. Pinion 28 meshes with the gear 19 and permits a further multiplication of speed. Moreover, if the teeth of the gear 19 be of larger pitch than it is practicable to use upon pinion 14, the pinion 28 may be of proper pitch for gear 19 and the gear 18 of a pitch equal to that of the 55 pinion 14. The casing 29 is of a form slightly different from casing 23 to accommodate and protect the change in form of drive, but it is assembled and held in substantially the same manner.

60 65 It will thus be seen that there is provided

apparatus in which the aims of this invention are achieved, and which, while permitting any desired multiplication of speed and full protection of the vulnerable parts, nevertheless imposes no strict limitations as to 70 the position of the generator and is adapted for use in the most crowded relations. The parts, moreover, are of the simplest and most durable construction and are of thoroughly reliable and quiet action. 75

As many changes could be made in the above construction and many apparently widely different embodiments of this invention could be made without departing from the scope thereof, it is intended that all 80 matter contained in the above description or shown in the accompanying drawings shall be interpreted as illustrative and not in a limiting sense.

It is also to be understood that the language used in the following claims is intended to cover all of the generic and specific features of the invention herein described and all statements of the scope of the invention, which, as a matter of language, might be said to fall therebetween. 85

Having described my invention, what I claim as new and desire to secure by Letters Patent is:

1. In apparatus of the class described, in 95 combination, a driving element, a driven element, and means for transmitting power between said elements at a constant ratio, said means being adjustably mounted with respect to the axis of one of said elements, 100 whereby said elements may be disposed at any suitable position relative to each other, and said power transmitting means adjusted to transmit power between said elements.

2. In apparatus of the class described, in 105 combination, a driving element, a driven element, a power transmitting member between said elements, and in permanent power transmitting relation with said driven element, said power transmitting member 110 being adjustable with respect to said driven element, whereby, for assembly, said driven element may be disposed at any suitable position relative to said driving element, and said power transmitting member moved 115 until it coacts in power transmitting relation with said driving element.

3. In apparatus of the class described, in combination, a supporting structure, a driving shaft thereon, a driving gear on said shaft, a power transmitting unit including four elements,—a driven shaft, a driven gear thereon, a support mounted for rotatable adjustment about said driven shaft, and an intermediate gear carried by said 120 support, and in permanent power transmitting relation to said driven gear, whereby, for assembly, the driven shaft may be disposed in any suitable position, relative to the driving shaft, and the power transmit- 125 130

ting relation established by rotating said support, until said intermediate gear comes into power transmitting relation with said driving gear.

5. In apparatus of the class described, in combination, a supporting structure, a first shaft fixed thereon, a second shaft which may be mounted in any suitable fixed position with respect thereto, and means for 10 transmitting power from one to the other said shaft, at a constant ratio, said means including an intermediate member for transmitting power between said shafts, permanently arranged in power transmitting relation with one of said shafts, and adjustable thereabout until it comes into power transmitting relation with the other said shaft.

15. In apparatus of the class described, in combination, a power driven shaft, a rotatable driving member upon said shaft, a

second shaft, a rotatable driven member thereon, a device mounted on said second shaft, a power transmitting member mounted on said device, and coöoperating with said driven member to permit said device to be 25 rotated to swing about said second shaft into a position in which said transmitting member transmits power from said driving member to said driven member and a casing member partially inclosing said transmission and leaving a portion of said power transmitting member exposed toward said driving member.

20. In testimony whereof I affix my signature, in the presence of two witnesses.

JOSEPH BIJUR.
